12 Claims. (Cl. 340—147)

This invention relates to electrical signalling systems with particular reference to their use in remote control and supervisory systems.

In remote control and supervisory systems it is frequently desirable to transmit two signals representing, respectively, the idle and the working conditions of a unit of apparatus. It is common practice to transmit over one line a succession of such signals, each successive signal referring to a different apparatus unit. In order that the signal relating to a particular apparatus unit may be directed to the desired apparatus unit in the case of a remote control system, or to supervisory equipment corresponding thereto in the case of a remote supervisory system, it is necessary that each individual signal should be separately identifiable. A common method of identifying these signals is with reference to their numerical position in a succession of signals, e.g., by arranging that the fourth signal of a succession relates to the fourth apparatus unit controlled or supervised. A known method of meeting these requirements is to connect a control and a remote station by a pair of conductors; to connect a battery across the conductors in one sense to provide one of the signalling conditions, e.g., apparatus unit idle; to connect the battery across the conductors in the opposite sense to provide the other signalling condition, e.g., apparatus unit working; and to disconnect the battery from the conductors between successive signals. That is to say three line conditions, which for simplicity may be referred to as "positive," "negative" and "zero," are required for the transmission of the requisite information.

Difficulty arises when the conductors are replaced, in whole or part, by a voice frequency telegraph system, as a signalling channel in such a system can generally assume only two states and one of these is assumed continuously when the channel is inoperative. When such a voice frequency system is introduced between a control and a remote station, either of two known arrangements may be used. Firstly, two voice frequency channels may be provided, in which case a "positive" condition is represented by the transmission of signalling tone over the first channel, "negative" by the transmission of signalling tone over the second channel, and "zero" by the inoperative tone on both channels simultaneously. Secondly, only one voice frequency channel may be used, in which case "positive" may be represented by a short pulse of signalling tone on the channel, and "negative" by a long pulse of signalling tone. The second arrangement suffers from the obvious disadvantage that the speed of transmission of information with such a system is inevitably slower than with two channels and that the delay will vary in accordance with the information transmitted. It is an object of the present invention to overcome this disadvantage without having

2

to provide a second voice-frequency channel, i.e., by using only two signalling conditions.

According to the invention there is provided a method of electric signalling between a transmitter and a receiver which employs two alternative signalling conditions and in which a signal includes an information time period during which either signalling condition may be transmitted in accordance with information which it is desired to transmit and at least a first change in signalling conditions.

- 5 10 15 20 25
- According to the invention there is also provided an electric signal transmitter having change-over switching means capable of performing at least a first change-over during a transmitted signal, and selection switching means operable to select for transmission during a signal either of two alternative signalling conditions before said first change-over and the other signalling condition after said first change-over.

According to the invention there is further provided an electrical signal receiver having change-over switching means responsive to a change from either to the other of two alternative received signalling conditions; two signal repeaters corresponding to the two signalling conditions, and each capable of selection to the exclusion of the other by an operation of the change-over switching means; and energizing means for the repeaters arranged to operate a repeater which has been selected.

The invention will now be described with reference to its application to a remote supervisory system, but it will be understood that the use of the signalling method 30 to be described is not restricted to either remote control or remote supervisory systems. Further, although suitable for use over a single voice-frequency channel, the method may be used with any signalling channel which will transmit at least two signalling conditions. In the following 35 description the signalling channel is described as a double-current duplex earth-return channel. Alternatively, the signalling channel could be part of a radio link.

In the description, reference will be made to the accompanying drawings in which:

- 40 45 50 55
- FIG. 1 shows the circuit arrangements at a control station.
- FIG. 2 shows circuit arrangements at a remote station.
- FIGS. 3, 4 are time charts showing the sequence of operations in the circuits of FIGS. 1, 2. For convenience, changes in signalling conditions are shown in both charts.
- The circuits shown in FIGS. 1 and 2 contain a multivibrator with a third winding and a follower relay (CY, CX in FIG. 1 and SY, SX in FIG. 2) of the type having a resistance-capacitance network associated therewith. These multivibrators can assume two conditions which may conveniently be designated "mark" and "space," and it is a feature of the multivibrators that the time during which a vibrator remains in one of these conditions is adjustable independently of the time during which it remains in the alternative condition, i.e., that the mark and space conditions need not have equal durations. This feature is made use of in the present invention.

OUTLINE OF OPERATION

- 60
- Throwing a control key (FIG. 1) at the control station initiates the operation of the multivibrator SY, SX (FIG. 2) at the remote station. At each cycle of operation of this multivibrator, a uniselector SW steps once and tests an apparatus unit connected to one of its bank contacts. Relays

SP, SN may or may not operate according to the state of the apparatus unit tested. Contacts *sp3*, *sn2* in conjunction with contact *ss4* determine whether positive or negative battery is applied to the point A, i.e., which of two alternative signalling conditions is to be transmitted. The duplex signalling channel identified in FIGS. 1, 2 as line is capable of assuming more than two conditions during signalling. However, in order to show clearly that the supervisory information is transmitted by the use of only two signalling conditions, the signalling conditions will be described in terms of the conditions applied to the point A. Contact *ss4* is operated by relay SS which, by its contact *ss1*, controls the stepping of the uniselector SW. The signalling conditions applied to point A are therefore related in time to the stepping of the uniselector SW. Referring to the time charts of FIGS. 3, 4, it will be seen that while the uniselector SW stands on one contact, the signalling condition applied to a point A refers to the uniselector contact previously tested.

As soon as the multivibrator SY, SX starts to operate, relay SS is also operated and contact *ss4* changes over. At the control station, relay CR (FIG. 1) responds to this change-over and releases the multivibrator CY, CX which performs one cycle and comes to rest, causing a uniselector CW to step to and dwell on its first contact. As already explained, contact *ss4* changes over in this manner once in each cycle of the multivibrator SY, SX. At each such change over, the multivibrator CY, CX operates once, and the uniselector CW steps once. Once in each cycle of the multivibrator CY, CX, the signalling conditions applied at point A cause one or other of relays CP, CN to operate, which in turn cause the lighting or extinguishing of supervisory lamps at the control station.

Referring again to FIGS. 3, 4 the supervisory information is transmitted as a succession of signals, each of which refers to one apparatus unit which has been tested. For convenience of description, each such signal may be divided into three equal time periods. At the end of the second period of each signal, relay SS is operated, which both prepares the uniselector SW to step to its next bank contact and causes the relay contact *ss4* to change over. The connections and operation of contacts *sp3*, *sn2* are such that this change-over always produces a change in the signalling conditions applied to the point A. At the end of the third time period of a signal, the relay SS is released, the uniselector SW steps once and contact *ss4* changes back. This may or may not produce a change of signalling conditions at point A depending on the positions taken up by contacts *sp3*, *sn2*. The signalling conditions applied as a result of contact *ss4* moving back are maintained for the first two periods of the next signal. These two periods together constitute the information time period of the signal. At the control station, the multivibrator, CY, CX starts a cycle of operation and the uniselector CW steps once, on the changeover of contact *ss4* at the end of each second time period. As already explained, contact *ss4* moves back at the end of each third time period. If, but only if, a change of signalling conditions results, the relay CR will respond and contact *cr1* will change over. The multivibrator CY, CX is adjusted so that contact *cr1* has time to operate before the multivibrator returns to mark. That is to say, the multivibrator CY, CX is adjusted to return to mark during the information time period of a received signal. When the multivibrator CY, CX returns to mark, contact *cx1* closes causing either relay CP or CN to operate depending on the position taken up by contact *cr1*. With the third winding of relay CY energised, the operation of multivibrator CY, CX is suspended. At the end of the second time period of an ensuing signal, relay CR operates once again in response to the change-over of contact *ss4*, and a further cycle of the multivibrator CY, CX is initiated.

The system comprises a transmitter (FIG. 2) and a receiver (FIG. 1), in which three signalling conditions are transmitted and received without requiring three signals of different amplitudes to indicate the three signalling conditions.

The transmitter generates a transmission signal including at least one information time period (for instance, time intervals 6, 7, and 8 or time intervals 9, 10, and 11, FIGS. 3 and 4) having at least one information signal portion and another information signal portion in sequence. To produce this transmission signal the transmitter includes a source of voltage having two output terminals, one of the output terminals providing a first voltage level, such as -80 volts associated with contact *sn2* of relay SN and with contact *sp3* of relay SP, and the other of the output terminals providing a second voltage level distinct from the first voltage level, such as +80 volts associated with contact *sn2* of relay SN and with contact *sp3* of relay SP.

The transmitter further comprises a first switching means including relay multivibrators SY, SX and their associated contacts and relay SS and its contact *ss4*. The cyclic operation of relay multivibrator SY, SX activates and deactivates relay SS to cause contact *ss4* to apply a -80 voltage to point A in its unoperated condition through contact *sp3* and a +80 voltage to point A in its operated condition through contact *sn2*. Thus, the first switching means is selectively coupled to the two output terminals of the voltage source to produce at the output (point A) of the first switching means at least a first change between the first voltage level and the second voltage level as the one information signal portion, this change between the two voltage levels being accomplished upon activation of relay SS by relay multivibrator SY, SX.

In addition, the transmitter includes a second switching means composed of relay SP and its contact *sp3*, relay SN and its contact *sn2*, and stepping relay SW and the testing contacts associated therewith. Through contacts *sp3* and *sn2* the second switching means is selectively coupled to the two output terminals of the source of voltage by stepping relay SW. The presence of an open or closed supervisory contact (SUP) selects one of the first and second voltage levels for coupling through contact *ss4* to point A, the output of the first switching means as another information signal portion.

Considering the operation of the transmitter during the time intervals 9, 10, and 11, an information time period, relay multivibrator SY, SX will be activated to place contacts *sy1* and *sx1* in the S condition to activate relay SS causing contact *ss4* to move from contact *sp3* to *sn2* and, hence from -80 volts to a +80 volts. This operation provides in the one information signal portion a changeover between -80 volts to +80 volts. Stepping relay SW will next test contact 3 and if it is assumed that the supervisory contact SUP3 is closed, relay SP and relay SN will be operated causing contacts *sn2* and *sp3* to assume their alternate positions so that when relay SS is deactivated by the reversal of the operating condition of multivibrator SY, SX, contact *ss4* will be returned to its normal indicated position. However, since relays SP and SN have been activated, contact *ss4* will be coupled through *sp3* to +80 volts which will maintain +80 volts at the output of the first switching means (point A). Thus, the transmitter is transmitting in one information signal portion a changeover between -80 volts and +80 volts and during another information signal portion the selection of +80 volts to be applied to the output (point A) of the first switching means.

Considering now time intervals 6, 7, and 8 constituting another information time period. Relay multivibrator SY, SX will be activated to its S condition to activate relay SS, thereby causing contact *ss4* to move from the illustrated position to its alternate position thereby changing from a -80 volts to a +80 volts due to contacts *sp3*

and $sn2$ being in their illustrated position. Upon the return of relay multivibrator SY, SX to its normal illustrated M condition, relay SS will be deenergized and contact $ss4$ will return to its normal indicated position, thereby causing a second changeover, but this time from +80 volts to -80 volts. This second changeover represents a third information portion of the information time period. Relays SP and SN will remain in their unenergized condition in this information time period since the stepping relay SW has landed on a contact whose supervisory switch is in the open condition and thereby prevents the energization of relays SN and SP and, thus, the another information signal portion is selected as -80 volts.

The information time period of the transmission signal at point A is transmitted through a transmission medium indicated as LINE and is presented to the receiver of FIG. 1 which includes therein a third switching means coupled to the transmission medium (LINE) including relay CR and its contact $cr1$. This third switching means is responsive to the first change of the one information signal portion and the selected one of the first voltage level and second voltage level of another information signal portion of the transmission signal for operation thereof.

The receiver in accordance with this invention further includes two means, relay CP and its contact and relay CN and its contact, each one of which represents one of the voltage levels. For instance, relay CP represents the -80 voltage level and relay CN represents the +80 voltage level. These two means are coupled to the third switching means through contact $cr1$ of the third switching means for exclusive selection of one of the two means by the third switching means during the operation thereof. The energizing means coupled to the third switching means through contact $cr1$ includes the inhibit winding of relay multivibrator CX, CY and their associated contacts $cx1$ and $cy1$.

Considering now the operation of the receiver during the information time period including time intervals 9, 10 and 11, the first change in the transmission signal from -80 volts to +80 volts will cause activation of relay CR and movement of its contact $cr1$ from the M to the S position, causing the relay multivibrator to be energized and to move its associated contacts from the M position to the S position to thereby deactivate the inhibit winding for a predetermined period. After this predetermined period relay multivibrator CX, CY will return to its M condition thereby applying through contact $cx1$ and the inhibit winding the activating voltage to contact $cr1$. Due to the fact that the signal being transmitted remains at +80 volts during time intervals 10 and 11, relay SR will remain energized and will hold contact $cr1$ in its S condition, thereby activating relay CN. Thus, relay CN is exclusively selected by the third switching means to indicate the presence of +80 volts in the another information portion.

Considering now the information time period including time intervals 6, 7, and 8. A first change of voltage from a -80 volts to a +80 volts will activate relay CR and move its contact $cr1$ from the M position to the S position to activate relay multivibrator CX, CY for its cyclic operation by removing the inhibiting voltage present at contact $cx1$ from the inhibit winding. Since a second change from a +80 volts to -80 volts occurs during these time intervals (third information portion) relay CR and relay multivibrator CX, CY will be deenergized and will return to its normal position and in effect will energize relay CP through the inhibit winding of relay multivibrator CX, CY and contact $cx1$. Since during time intervals 7 and 8 the voltage levels being sent from the transmitter to the receiver is a -80 volts, relay CR will remain unenergized, contact $cr1$ will remain in its M condition and, hence, relay CP will remain selected or activated to indicate the presence of -80 volts in the another information portion, this selection being exclusively controlled by the third switching means.

DETAILED DESCRIPTION

In the following description, it will be convenient to consider each signal as divided into three equal time periods. The multivibrator SY, SX at the remote station is arranged to have a mark-to-space ratio of 2:1; while the multivibrator CY, CX at the control station has a ratio of 1:2. These ratios, however, are used for descriptive purposes only, and in practice any suitable ratios could be used.

10 The signals will be described in connection with the transmission of supervisory information from a remote station to a control station, that is to say, with reference to the signalling conditions applied to the point A (FIG. 2) for transmission to the control station. In the example to be described, the transmission of information is controlled by the operation of a control key at the control station. When the control key is operated, the resulting signal is transmitted to the remote station over a duplex channel (line) capable of transmitting signals in both directions at the same time. However, if the signalling channel connecting the two stations is capable of assuming only two signalling conditions, as is the case with a voice-frequency telegraph signalling channel, and if only one such channel is provided, it would be necessary to provide directional switching equipment at each end of the channel so that the channel could be worked first in an outward direction for transmitting the control signal and then in an inward direction for transmitting the signals conveying the supervisory information. Such directional switching equipment is well known in the art and will not be described here.

35 The apparatus at the remote station includes a free-running multivibrator SY, SX arranged to start in response to a suitable starting signal, in this case the throwing of a control key at the control station. Also provided is a uniselector SW which steps under the control of the multivibrator SY, SX and tests each bank contact while it dwells thereon. The condition of each bank contact 40 is determined by whether a supervisory contact, connected thereto and indicative of the state of an apparatus unit to be supervised, is open or closed, e.g., the condition of bank contact 3 is determined by the open or closed condition of supervisory contact SUP3, which, in turn, is determined by the condition of an apparatus unit associated therewith. If the contact SUP3 is closed when the uniselector SW steps on the bank contact 3, relay SP will be energized followed by relay SN. On the other hand, if the contact SUP3 is open, neither relay will be energized. Relays SP, SN respond to the condition of each bank contact in turn and by means of their contacts $sp3$, $sn2$ determine, in conjunction with contact $ss4$, the signalling conditions applied to the point A. While the uniselector SW stands on one bank contact, a signal relating to the preceding bank contact is transmitted.

55 At the control station, a multivibrator CY, CX operates on a start-stop basis and performs one cycle for each cycle of the multivibrator SY, SX at the remote station. A uniselector CW steps under the control of the multivibrator CY, CX. While the uniselector CW is standing on one bank contact, one of the relays CP, CN is operated depending upon the signalling condition applied to the point A in relation to the corresponding bank contact of the uniselector SW at the remote station. A red and a green supervisory lamp is provided at the control station for each apparatus unit supervised at the remote station. In the example, when a supervisory contact is open the corresponding green lamp glows, and when the supervisory contact is closed the corresponding red lamp is lit and the green lamp is extinguished.

60 The interaction of the two multivibrators and of the relays and uniselectors associated therewith will be more easily understood by referring to the time chart shown in FIGS. 3, 4 which also serves to illustrate the nature of 65 the signals transmitted. For ease of reference, the op-

eration of the equipment will be described stage by stage in a series of time periods numbered from 0 upwards. In the example, a signal consists of three successive time periods, e.g., 4, 5, 6. During the period 4, 5, 6 the uniselector SW stands on bank contact 2 while the signal relating to bank contact 1 is transmitted. During the first two periods 4, 5 of this signal, the signalling conditions applied to the point A (FIG. 2) for transmission to the control station are determined by which of two alternative conditions is extended over contact *sp3* when contact *ss4* is restored. These periods 4, 5 together constitute an information time period during which the supervisory information from bank contact 1 of uniselector SW is transmitted to the control station and during which, e.g., at the end of period 4, the multivibrator CY, CX, at the control station returns to mark to operate one or other of relays CP, CN. At the end of period 5, relay SS at the remote station is energized. The connections and operation of contacts *sp3* *sn2* are such that the resulting operation of contact *ss4* always causes a change of signalling conditions at point A, which change is used to initiate a cycle of the multivibrator CY, CX at the control station. At the end of the third period 6, contact *ss4* is restored. If the next signal to be transmitted is the same as the last, as is the case if both bank contacts 1, 2 when tested are found in the same condition, the restoration of contact SS4 causes a further change in the signalling condition applied to the point A. On the other hand, if the bank contacts were not in the same condition, the restoration of contact *ss4* does not cause a change of signalling conditions at point A. It is to be understood that the division of a signal into equal time periods was made arbitrarily and for ease of description and is not essential. The two essential features of a signal are, firstly, an information time period during which either of two alternative signalling conditions is applied for transmission and, secondly, a change-over in signalling conditions. The direction of the change-over is not important, that is to say it may be either from a first to a second signalling condition, or from the second to the first condition. Neither is it of importance whether the information time period of a signal precedes or follows the change-over provided the circuits of the transmitter and receiver are suitably designed. In order that the same signalling condition may be applied during the information time period of successive signals, a signal may contain a second change of signalling conditions, e.g., at the end of the period 6 in the signals 4, 5, 6, in addition to the two essential features mentioned.

In FIGS. 1, 2, all relays with more than one winding are shown in the mark condition, the arrows indicating the direction of flow of marking current in the individual windings. Single-winding relays are shown in the released condition. When no information is being transmitted, relay CP is energized and its contacts are in the opposite positions to those shown, while the contacts of other relays are in the positions indicated. When no information is being transmitted, each of the multivibrators is held inoperative by an inhibiting current flowing in its third winding. At the control station, this current also energises relay CP.

In FIGS. 3, 4, a shaded area represents a lapse of time during which a piece of equipment, such as a relay, a key or a contact, is in a condition other than that depicted in FIGS. 1, 2. For the purposes of description, it will be assumed that the supervisory contact SUP3 (FIG. 2) has been closed before the commencement of the operations to be described. It will also be assumed that the supervisory contacts connected to the other bank contacts of the uniselector SW are all open.

To initiate the transmission of supervisory information, the control key at the control station is thrown, applying negative battery to line. Thereafter the following operations occur in the time periods indicated, 75

the time periods being numbered in accordance with FIGS. 3, 4.

Time period 0

Remote station.—Relay SR operates to space and remains at space so long as the control key is thrown. Contact *sr1* opens, interrupting the inhibiting current flowing in the third winding of relay SY. The multivibrator, consisting of relay SY and its follower relay SX, is released, changing to space and starting to run freely. With contact *sr1* at space, relay SS is energized, closing contact *ss1* and energizing the drive magnet of the uniselector SW. The uniselector SW, however, does not step, being of the type which steps on the release of the driving magnet. When relay SS is energized, contact *ss4* changes over, changing the signalling condition at point A from negative over contact *sp3* to positive over contact *sn2*.

Control station.—Relay CR changes to space in response to the change in signalling condition at point A. In moving from mark to space, contact *cr1* interrupts the inhibiting current through the third winding of relay CY. Relay CY, followed by relay CX, changes to space. The change-over of contact *cr1* also releases relay CP. By the time contact *cr1* has moved to space and contact *cp3* has closed, contact *cx1* has moved to space. When contact *cp1* has closed, the slow-to-release guard relay CG is energized. The slow release facility enables the relay CG to remain operated during periods when its energizing circuit is interrupted by the opening of either of the contacts *cp1*, *cn1*. The operation of contacts *cg1*, *cg2* is ineffective at this stage.

Time period 1

Remote station.—This period is initiated when the multivibrator SY, SX returns to mark of its own accord. The opening of contact *sr1* releases relay SS. The opening of contact *ss1* releases the drive magnet of the uniselector SW which steps to bank contact 1. The restoration of contact *ss4* changes the signalling condition at point A from positive over contact *sn2* to negative over contact *sp3*.

Control station.—Relay CR changes to mark in response to the change in signalling condition at the point A. Contact *cr1*, in moving to mark, prepares a circuit for the operation of relay CP.

Time period 2

Remote station.—The conditions established during time period 1 are maintained unchanged.

Control station.—The period is initiated when the multivibrator CY, CX returns to mark of its own accord. For ease of description, the return to mark is regarded as taking place in the middle of the combined period 1-2. However, the return may take place at any convenient time after relay CR has had time to operate. When the multivibrator returns to mark, contact *cx1* moves to mark. Current then flows over contact *cx1* at mark, through the third winding of relay CY, over contact *cr1* at mark, contact *cn3* and then through relay CP. This current inhibits the multivibrator, which is thereby held in the mark condition. The current also energizes relay CP. Contact *cp1* opens, but relay CG, being slow to release, remains operated until this contact closes again. With contact *cg1* operated, the closing of contact *cp2* energizes the driving magnet of the uniselector CW. The uniselector CW, however, does not step, being of the type which steps on the release of the driving magnet.

Time period 3

Remote station.—This period is initiated when the multivibrator SY, SX changes to space of its own accord. As before, relay SS and magnet SW are energized. The closing of contact *ss2* tests bank contact 1 on which the uniselector SW is now standing. Since the supervisory contact connected to this bank contact is open,

relay SP does not operate. The closing of contact *ss3* prepares a hold circuit for relay SN, which however is not operated at this juncture. When contact *ss4* changes over, the signalling condition at point A is changed from negative over contact *sp3* to positive over contact *sn2*.

Control station.—Relay CR changes to space in response to the change in signalling condition at point A. As before, the change-over of contact *cr1* deenergizes relay CP and releases the multivibrator, which moves to space. The opening of contact *cp2* deenergizes the drive magnet of uniselector CW which steps to bank contact 1.

Time period 4

Remote station.—This period is initiated when the multivibrator SY, SX returns to mark of its own accord. As before, relay SS is released, magnet SW is deenergized, and the uniselector SW steps to bank contact 2. This contact, however, is not tested until contact *ss2* is closed in time period 6.

The restoration of contact *ss4* applies to point A a signalling condition dependent on the position of contact *sp3*, which in turn is determined by whether or not relay SP was operated when bank contact 1 was tested. Since, however, relay SP was not operated, the restoration of contact *ss4* changes the signalling condition from positive over contact *sn2* to negative over contact *sp3*.

Control station.—Relay CR changes to mark in response to the change in signalling conditions at point A. As before, contact *cr1*, in moving to mark, prepares a circuit for the operation of relay CP.

Time period 5

Remote station.—The conditions established during time period 4 are maintained unchanged.

Control station.—The period is initiated when the multivibrator CY, CX returns to mark of its own accord. As before, the multivibrator is inhibited and relay CP is energized. The closing of contact *cp2* energizes the drive magnet CW over contact *cg1* operated. Since contact *cn4* is not operated, relay C1A (not shown, but which is connected to bank contact 1 in the same way as relay C3A is connected to bank contact 3) is not energized. Consequently its contact *c1a2* (not shown, but which is connected similarly to contact *c3a2*) is not operated. Hence, the green lamp corresponding to bank contact 1 continues to glow.

Time period 6

Remote station.—This period is initiated when the multivibrator SY, SX changes to space of its own accord. As before, relay SS and magnet SW are energized. Relay SP does not operate, since it is assumed that the supervisory contact connected to bank contact 2, on which the uniselector SW is now standing, is open. When contact *ss4* changes over, the signalling condition at point A is changed from negative over contact *sp3* to positive over contact *sn2*.

Control station.—Relay CR changes to space in response to the change in signalling condition at point A. As before, the change-over of contact *cr1* deenergizes relay CP, and release the multivibrator which moves to space. The opening of contact *cp2*, as previously, deenergizes the drive magnet of the uniselector CW which steps to bank contact 2.

Time period 7

Remote station.—This period is initiated when the multivibrator SY, SX returns to mark of its own accord. As before, relay SS is released. The uniselector SW steps to bank contact 3. With the supervisory contact SUP3 assumed closed, positive battery appears on bank contact 3, but this is ineffective at this stage since contact

ss2 is not operated. Since relay SP was not operated when bank contact 2 was tested, the restoration of contact *ss4* changes the signalling condition at point A from negative over contact *sp3* to positive over contact *sn2*.

5 *Control station*.—Relay CR changes to mark in response to the change in signalling conditions at point A. As before, contact *cr1*, in moving to mark, prepares a circuit for the operation of relay CP.

Time period 8

Remote station.—The conditions established during time period 7 are maintained unchanged.

Control station.—The period is initiated when the multivibrator CY, CX returns to mark of its own accord. 15 As before, the multivibrator is inhibited and relay CP and the drive magnet CW are energized. The green lamp corresponding to bank contact 2 continues to glow.

Time period 9

Remote station.—This period is initiated when the multivibrator SY, SX changes to space of its own accord. As before, relay SS and magnet SW are energized, and the change-over of contact *ss4* changes the signalling condition at point A from negative over contact *sp3* to positive over contact *sn2*.

25 With the uniselector SW standing on bank contact 3, the operation of contact *ss2* causes relay SP to be energized, since supervisory contact SUP3 is assumed closed. The closing of contact *sp1* prepares a hold circuit for relay SP. The closing of contact *sp2* prepares an operating circuit for relay SN. The change-over of contact *sp3* prepares the connection of positive battery to point A in time period 10.

30 *Control station*.—As before, relay CP changes to space in response to the change of signalling conditions at the point A. As before, the change-over of contact *cr1* de-energizes relay CP, and releases the multivibrator which moves to space. As before, the drive magnet CW is released. The uniselector CW steps to bank contact 3.

Time period 10

Remote station.—This period is initiated when the multivibrator SY, SX returns to mark of its own accord. As before, relay SS is released. This time, the restoration

45 of contact *ss4* does not cause a change in signalling conditions at point A, since, this time, contact *sp3* is operated. With contact *sp3* operated and contact *ss4* restored, positive battery is connected to point A during time periods 10, 11, which together constitute the information time period of the signal relating to bank contact 3.

50 The opening of contact *ss1* deenergizes the magnet of the uniselector SW which steps to bank contact 4. The restoration of contact *ss2* completes a hold circuit for relay SP over its own contact *sp1* operated. On the

55 restoration of contact *ss3*, relay SN is energized over contact *sp2* operated. The closing of contact *sn1* prepares a hold circuit for relay SN. The change-over of contact *sn2* ensures a change of signalling conditions at point A when relay SS is next operated and contact *ss4* changes over at the beginning of time period 12.

60 *Control station*.—Since there was no change in signalling conditions at point A, the conditions of time period 9 are maintained unchanged. In particular, relay CR and its contact *cr1* remains at space, thereby preparing a circuit for the operation of relay CN instead of relay CP.

Time period 11

Remote station.—The conditions established during time period 10 are maintained unchanged.

Control station.—The period is initiated when the multivibrator CY, CX returns to mark of its own accord. As before, when contact *cx1* returns to mark, the multivibrator is inhibited by current flowing through the third

11

winding of relay CY. This time, since contact *cr1* is at space, relay CN is operated in series with the third winding of relay CY. The drive magnet CW is energized over contacts *cn2*, *cg1* both operated. With the uniselector CW standing on bank contact 3 and with contacts *cn4*, *cg2* both closed, relay C3A is energized in series with resistor R3. Relay C3A locks in series with its own contact *c3a1* operated and resistor R3. The change-over of contact *c3a2* extinguishes the green lamp corresponding to bank contact 3 and lights the corresponding red lamp.

Time period 12

Remote station.—This period is initiated when the multivibrator SY, SX changes to space of its own accord. As before, relay SS and magnet SW are energized. The change-over of contact *ss4* changes the signalling condition at point A, this time, from positive over contact *sp3* operated to negative over contact *sn2* operated. With the uniselector SW now standing on bank contact 4, the operation of contact *ss2* breaks the hold circuit for relay SP over contact *sp1*. The operation of contact *ss3* completes a hold circuit for relay SN. The release of relay SP restores contacts *sp1*, *sp2*, *sp3*.

Control station.—In response to the change of signalling conditions at point A, relay CR changes, this time, from space to mark. The change-over of contact *cr1* deenergizes relay CN and releases the multivibrator which moves to space. The opening of contact *cn2* deenergizes the drive magnet of the uniselector CW which steps to bank contact 4.

Time period 13

Remote station.—This period is initiated when the multivibrator SY, SX returns to mark of its own accord. As before, relay SS is released. This time, the release of contact *ss4* does not cause a change of signalling conditions at A, negative battery being applied before the release over contact *sn2* (operated since time period 10) and after the release over contact *sp3* (restored in time period 12). The opening of contact *ss1* results in the uniselector SW stepping to bank contact 5. The restoration of contact *ss2* is ineffective since relay SP was released in time period 12. The restoration of contact *ss3* breaks the hold circuit for relay SN which releases.

Control station.—As there is no change in signalling condition at point A, relay CR is not operated and remains at mark. The conditions established during time period 12 are maintained unchanged.

Time period 14

Remote station.—The conditions established during time period 13 are maintained unchanged.

Control station.—The period is initiated when the multivibrator CY, CX returns to mark of its own accord. As before, when contact *cx1* moves to mark, the multivibrator is inhibited and relay CP is energized.

Time period 15 onwards

Remote station.—Time period 15 is initiated when the multivibrator SY, SX changes to space of its own accord. The change-over of contact *ss4* changes the signalling condition at point A from negative over contact *sp3* (restored in time period 12) to positive over contact *sn2* (restored in time period 13). Thereafter the action continues in the manner already described.

Control station.—As before, relay CR changes to space in response to the change of signalling conditions at point A. Thereafter the action continues in the manner already described.

Both stations.—The action just described is repeated until control key at the control station is restored. When this occurs, relay SR is operated to mark. The movement of contact *sr1* to mark is ineffective at this stage, since

12

wiper *sw1* is not standing on bank contact 0. The multivibrator SY, SX continues to operate and the uniselector SW continues to step, as do similarly the multivibrator CY, CX and the uniselector CW, until the uniselector SW steps on to bank contact 0. When this occurs, inhibiting current flows over contact *sr1* at mark, wiper *sw1* and the third winding of relay SY. The multivibrator SY, SX and the uniselector SW come to rest. At the control station, inhibiting current flows through the third winding of relay CY in series with relay CP (or CN) as already described. The operation of the multivibrator CY, CX is inhibited, but the uniselector CW is one bank contact behind the uniselector SW. However, the continued energization of relay CP (or CN) holds contact *cp1* (or *cn1*) open and relay CG is released. Contact *cg1* restores and completes a homing circuit for the uniselector CW which includes the drive magnet CW, the make and break contact *mb* and the third bank of uniselector CW having a common bank contact for all bank contacts of the other banks (CW1 and CW2) except the home contact 0. When wiper *sw3* steps on to bank contact 0, the uniselector CW comes to rest.

Second cycle

Now suppose that the supervisory contact SUP3 is opened before the control key is operated for the second time. Under these conditions, when bank contact 3 is tested by the uniselector SW, relay SP will not operate. The signal relating to bank contact 3, will consist of an information time period (time periods 10, 11) in which, this time, negative battery is applied to point A, together with a change in signalling conditions at the beginning of time period 12. There will also, this time, be a second change in signalling conditions at the beginning of time period 13. At the control station, the relay CN will, this time, not be operated during the information time period of the signal for bank contact 3. Relay CP, however, will be operated in the manner already described. The closing of contact *cp4* completes a short circuit for relay C3A. The short circuit includes contact *c3a1* operated, wiper *sw1*, contacts *cg2*, *cp4* both operated, wiper *sw2* and resistor R3. Relay C3A releases. The opening of contact *c3a1* breaks the circuit by which relay C3A was held operated. The restoration of contact *c3a2* extinguishes the red lamp corresponding to bank contact 3 and lights the corresponding green lamp. Thereafter the action is as already described.

While the principles of the invention have been described above in connection with specific apparatus, it is to be clearly understood that this description is made only by way of example and not as a limitation on the scope of the invention.

What we claim is:

1. An electric signal system comprising:
a transmitter to generate a transmission signal including at least one information time period having at least one information signal portion and another information signal portion in sequence, said transmitter including
a source of voltage having two output terminals, one of said output terminals providing a first voltage level and the other of said output terminals providing a second voltage level distinct from said first voltage level,
a first switching means selectively coupled to said two output terminals to produce at the output of said first switching means at least a first change between said first voltage level and said second voltage level as said one information signal portion, and
a second switching means selectively coupled to said two output terminals to select one of said first voltage level and said second voltage level for coupling to said output of said first switch-

13.

- ing means as said another information signal portion;
- a transmission medium coupled to said output of said first switching means for propagation of said transmission signal; and
- a receiver including
- a third switching means coupled to said transmission medium responsive to said first change of said one information signal portion and said selected one of said first voltage level and said second voltage level of said another information signal portion of said transmission signal for operation thereof,
  - two means each representing one of said first voltage level and said second voltage level coupled to said third switching means for exclusive selection of one of said two means by said third means during the operation thereof, and
  - energizing means coupled to said third switching means to activate the selected one of said two means.
2. An electric signal transmitter to generate a transmission signal including at least one information time period having at least one information signal portion and another information signal portion in sequence comprising:
- a source of voltage having two output terminals, one of said output terminals providing a first voltage level and the other of said output terminals providing a second voltage level distinct from said first voltage level;
  - a first switching means selectively coupled to said two output terminals to produce at the output of said first switching means at least a first change between said first voltage level and said second voltage level as said one information signal portion;
  - a second switching means selectively coupled to said two output terminals to select one of said first voltage level and said second voltage level for coupling to said output of said first switching means as said another information signal portion; and
  - a transmission medium coupled to said output of said first switching means for propagation of said transmission signal.
3. A transmitter according to claim 2, wherein said first switching means produces at said output of said first switching means a third information signal portion for said information time period in sequence with said one and said another information signal portions including a second change between said first voltage level and said second voltage level; and
- said second switching means remain inoperative to select a given one of said first voltage level and said second voltage level as said another information signal portion.
4. A transmitter according to claim 2, further including testing means coupled to said second switching means for testing in sequence the condition of each of a plurality of test terminals to operate said second switching means in accordance with the condition of the successive test terminals tested;
- driving means coupled to said first switching means and said testing means to control the sequential testing of said testing means; and
- said first and second switching means cooperate to generate said transmission signal having in sequence a plurality of said information time periods, each of said information time periods including as said one information signal portion said first change and the presence or absence of a second change between said first voltage level and said second voltage level as determined by the condition of said test terminal previously tested, and as said second information period one of said first voltage level and said second

14.

- voltage level as determined by the condition of said test terminal tested.
5. An electric signal receiver comprising:
- a transmission medium to propagate a transmission signal including at least one information time period having at least one information signal portion including at least a first change between a first voltage level and a second voltage level distinct from said first voltage level and another information signal portion in sequence with said one information signal portion including a selected one of said first voltage level and said second voltage level;
  - a switching means coupled to said transmission medium responsive to said first change of said one information signal portion and said selected one of said first voltage level and said second voltage level of said another information signal portion of said transmission signal for operation thereof;
  - two means each representing one of said first voltage level and said second voltage level coupled to said switching means for exclusive selection of one of said two means by said switching means during operation thereof; and
  - energizing means coupled to said switching means to activate the selected one of said two means.
6. A receiver according to claim 5, wherein
- said transmission signal includes in said one information signal portion a second change between said first voltage level and said second voltage level;
- said switching means is responsive to said first change in said one information signal portion to initiate operation thereof;
- said energizing means includes
- a delay device coupled to said switching means activated by said switching means upon the initiation of operation thereof to provide a predetermined time delay before said selected one of said two means is activated by said energizing means; and
  - said switching means responds to said second change during said predetermined time delay to select the appropriate one of said two means.
7. A receiver according to claim 6, wherein
- said transmission signal includes in sequence a plurality of said information time periods; and
- said receiver further includes
- a plurality of indicators each representing one of said plurality of said information time periods and having two states, one of said states corresponding to one of said first voltage level and said second voltage level and the other of said states corresponding to the other of said first voltage level and said second voltage level; and
  - a distributor coupled to said two means and said plurality of indicators controlled by the repetitive operation of said delay device to sequentially engage each of said indicators, the state of any one of said indicators being determined by which of said two means is activated during the period of engagement by said distributor.
8. An electric signal system comprising:
- a transmitter including
- a first monostable relay multivibrator activated in response to a control signal;
  - a control relay coupled to said first multivibrator, said first multivibrator controlling the operating condition of said control relay;
  - a first uniselector;
  - a first contact controlled by said control relay coupled to said first uniselector to successively test the condition of a plurality of devices;
  - first and second test relays;
  - a source of voltage having two outputs, each output providing a different voltage level, one of said voltage levels providing a first signalling

- condition and the other of said voltage levels providing a second signalling condition, a second contact controlled by said first test relay to be selectively connected to said outputs of said source of voltage; 5 a third contact controlled by said second test relay to be selectively connected to said outputs of said source of voltage; a fourth and fifth contacts controlled by said control relay interconnecting said first uniselector and both said test relays to render said test relays responsive to the condition of the device tested by said first uniselector; a transmission medium; and a sixth contact controlled by said control relay to 15 be sequentially coupled to said second and third contacts to supply to said transmission medium a transmission signal having a duration equal to the energization-deenergization cycle of said control relay including a first change between said first and second signalling conditions upon energization of said control relay, one of said first and second signalling conditions as determined by the condition of the device tested by said first uniselector and the presence or absence of a 25 second change between said first and second signalling conditions as determined by the condition of the device previously tested by said first uniselector upon deenergization of said control relay; and 30 a receiver coupled to said transmission medium including switching means having two contacts responsive to said transmission signal; a first relay coupled to one of said contacts of 35 said switching means; a second relay coupled to the other of said contacts of said switching means; a second monostable relay multivibrator including inhibiting winding coupled to said switching means responsive to said first change of said transmission signal to render said second multivibrator operative and to select one of said two contacts of said switching means in accordance with which of said first and second signalling 45 conditions is present; a seventh contact controlled by said second multivibrator in series with said inhibiting winding, said seventh contact closing after a delay determined by the operating time of said second multivibrator to establish a connection for an inhibiting current through said inhibiting winding, said switching means and one of said first and second relays depending upon which of said contacts of said switching means is selected to 50 render one of said first and second relays operative; a second uniselector including a plurality of contacts coupled to said first and second relays; means coupled to said first and second relays and 60 said second uniselector to step said second uniselector sequentially to each of said plurality of contacts at each interruption of said inhibiting current; and a plurality of indicators each coupled to one of said 65 plurality of contacts of said second uniselector operable to one of two states in accordance with which of said first and second relays is rendered operative. 9. A system according to claim 8, wherein said control signal is transmitted from said receiver to said transmitter over said transmission medium. 70 10. An electric signal transmitter comprising: a monostable relay multivibrator activated in response to a control signal;

- a control relay coupled to said multivibrator, said multivibrator controlling the operating condition of said control relay; a testing uniselector; a first contact controlled by said control relay coupled to said uniselector to successively test the condition of a plurality of devices; first and second test relays; a source of voltage having two outputs, each output providing a different voltage level, one of said voltage levels providing a first signalling condition and the other of said voltage levels providing a second signalling condition; a second contact controlled by said first test relay to be selectively connected to said outputs of said source of voltage; a third contact controlled by said second test relay to be selectively connected to said outputs of said source of voltage; fourth and fifth contacts controlled by said control relay interconnecting said uniselector and both said test relays to render said test relays responsive to the condition of the device tested by said uniselector; a transmission medium; and a sixth contact controlled by said control relay to be sequentially coupled to said second and third contacts to supply to said transmission medium a transmission signal having a duration equal to the energization-deenergization cycle of said control relay including a first change between said first and second signalling conditions upon energization of said control relay, one of said first and second signalling conditions as determined by the condition of the device tested by said uniselector and the presence or absence of a second change between said first and second signalling conditions as determined by the condition of the device previously tested upon deenergization of said control relay. 11. A transmitter according to claim 10, wherein said control signal for activating said multivibrator is received at said transmitter from a remote location over said transmission medium. 12. An electric signal receiver comprising: switching means having two outputs responsive to received signals including information in the form of one of two distinct signalling condition and at least one change between said two signalling conditions to select one of said two outputs in accordance with which of said two signalling conditions is present; a first relay coupled to one of said outputs; a second relay coupled to the other of said outputs; a monostable relay multivibrator including an inhibiting winding coupled to said switching means; a contact controlled by said multivibrator in series with said inhibiting winding, said contact closing after a delay determined by the operating time of said multivibrator to establish a connection for an inhibiting current through said inhibiting winding, said switching means and one of said first and second relays depending upon which of said outputs is selected; a uniselector including a plurality of contacts coupled to said first and second relays; means coupled to said first and second relays and said uniselector to step said uniselector sequentially to each of said plurality of contacts at each interruption of said inhibiting current caused by said change between said two signalling conditions; and a plurality of indicators each coupled to one of said plurality of contacts operable to one of two states in accordance with which of said first and second relays is rendered operative.
